UNITED STATES PATENT OFFICE.

EARL J. MOBLEY, OF GOLDDENDALE, WASHINGTON.

DESIGN FOR A POISON-BOTTLE.

45,674.

Specification for Design.

Patented Apr. 28, 1914.

Application filed January 20, 1914. Serial No. 813,339. Term of patent 7 years.

To all whom it may concern:

Be it known that I, EARL J. MOBLEY, a citizen of the United States, residing at Goldendale, in the county of Klickitat and State of Washington, have invented a new, original, and ornamental Design for Poison-Bottles, of which the following is a specification, reference being had to the accompanying drawing, forming part thereof.

In the accompanying drawings:—Figure 1 is a side view looking at one side of the

bottle and showing my new design; and Fig. 2 is a similar view looking at the opposite side of the bottle.

I claim:—

The ornamental design for a poison bottle, as shown.

EARL J. MOBLEY.
